UNITED STATES PATENT OFFICE

FREDERIC F. BAHNSON, OF WINSTON-SALEM, NORTH CAROLINA

AIR-CONDITIONING APPARATUS

Application filed March 2, 1927. Serial No. 172,107.

This invention relates to air conditioning apparatus of semi-portable type which may be located in any desired part of a room, and which may be used in any number required in 5 any room or space wherein it is desired to maintain the air in proper condition.

An object of the invention is to provide an air conditioning apparatus, having the attributes just recited, which will be effective to 10 heat or to humidify the air, or both to heat and moisten or humidify the air as the temperature and humidity thereof may require.

The invention consists in the combination with air circulating means, such as a fan, of 15 air heating means, such as a tubular, fluid heated, heat exchanger, and air moistening means, such as a humidifier of well known type, by which water is atomized or pulverized and fed to a current of air produced by 20 the air-circulating means, the operation of these devices being preferably automatically controlled by temperature and humidity responsive devices, respectively, in accordance with the condition of the surrounding air.

25 In the accompanying drawings illustrating the invention, in the several figures of which like parts are similarly designated,

Fig. 1 is a sectional elevation showing the complete apparatus;

30 Fig. 2 is an elevation looking toward the left of Fig. 1;

Fig. 3 is a sectional elevation of the heater unit taken on line 3—3 of Fig. 1; and

35 Fig. 4 shows a modified form of the apparatus wherein it is arranged upon a vertical axis rather than a horizontal axis as in Figs. 1 and 2.

The apparatus comprises an air circulating device or fan 1 driven preferably by an electric motor 2 and adapted to set up a current 40 of air in the direction of the arrow *a*, Fig. 1.

Combined with this fan 1 and motor 2 is 45 an air moistening or humidifying device 3 having deflectors 4 and 5 and a rotary spraying disc 6, the latter being driven by the motor 2. This disc 6 receives water, in predetermined requisite quantity, at a point adjacent to the axis of rotation, through a nozzle 7 fed by a water pipe 8, and the water is projected 50 by centrifugal force from the periphery of

the disc against a plurality of circularly arranged baffles or vanes 9 by which it is broken up or pulverized and thus put in condition to be picked up by the current of air produced by the fan 1. Any excess of water will be 55 caught by the deflector 5 and directed into a drip-pan 10 from which it may drain to waste.

The parts thus far described are of well-known type and are sufficiently shown and described in my Patent No. 1,544,418, granted 60 June 30, 1925, to require no further detailed description here.

Directly in the path of the current of air induced by the fan 1, and in advance of the fan, I arrange an air heating device comprising, in the form shown, a heat radiator or exchanger having a casing 11 provided with an upper chamber 12 and a lower chamber 13, these two chambers being connected by a plurality of tubes 14 arranged in staggered relation, as shown particularly in Fig. 3, to provide tortuous air paths through the heater.

Steam, or other heating fluid, (but I prefer to use steam) is introduced into the heater at the chamber 12 through a pipe 15 and, passing through the tubes 14, reaches chamber 13 from which it, or water of condensation, may escape through a pipe 16.

75 The air passing through the heater is directed to the air moistener or humidifier by 80 means of a casing or funnel 17.

The whole apparatus thus far described may be suitably supported from the ceiling of the room or from any other desired support by a framework 18 to which are secured the 85 clamps 19 of a bracket 20 which provides a carrier for the various parts.

Mounted in any appropriate location in the room or space in which the air is to be conditioned are a thermostat 21 and a humidostat 90 22. The thermostat is interposed in an electric circuit which operates a valve 23 in the heater pipe 15, and the humidostat is interposed in an electric circuit which operates a valve 24 in the water pipe 8. Both of these 95 circuits are in series with the motor 2 through an appropriate switch mechanism 25 and each circuit may therefore energize the motor independently of the other.

100 This particular electrical circuit is to be un-

derstood as illustrative of the type of control which is contemplated. Suitable low voltage relay circuits may be employed in place of the line or motor circuit for operating the valves.

- 5 As shown in Figs. 1 and 2, the apparatus is arranged upon a horizontal axis, but it is possible that in some installations it might be desirable to have it arranged upon a vertical axis, and such an arrangement is shown in 70 Fig. 4. But the essential details of the apparatus and its controls are the same in both forms.

10 However, in the form shown in Fig. 4, the deflector 5', in addition to its action in catching the spray of water particles from the disc 6 as they are broken up by the vanes 9 upon its inner surface, is so designed that its outer surface acts as a deflector to distribute the air circumferentially.

15 20 From the foregoing description it is believed that the operation of my invention will be obvious, but in the interest of clearness such operation may be stated as follows:— The thermostat is responsive to the room 25 temperature, and the humidostat is responsive to the room humidity and they are set to operate whenever such temperature and humidity deviate from certain predetermined desirable points.

20 25 30 If the percentage of humidity is too low, the humidostat will operate to close the circuit through the valve 24 and motor 2. This will operate the fan 1 and rotate disc 6 and will, simultaneously, open valve 24 to supply water to disc 6 through pipe 8 and nozzle 7. When the predetermined desired percentage of humidity is thus reestablished, the humidostat will break the circuit through the motor and valve thereby stopping the feed 35 of moisture to the air.

35 40 45 If the room temperature is too low, the thermostat will operate to close a circuit through the motor 2 and valve 23, thus starting the fan and opening the valve 23 to admit heating fluid to the heater, to thereby circulate air through the heater in contact with the heated tubes thereof. When the predetermined room temperature is thus reestablished, the thermostat will open the circuit 50 and consequently the motor will be de-energized and the feed of heating fluid to the heater will be cut off by the automatic closing of valve 23.

55 60 Obviously, the air-moistening means and the air-heating means may operate simultaneously to both heat and humidify the air of the room, in which case both of the valves 23 and 24 will be open, and the motor, with the fan and disc driven thereby, operating.

65 70 75 My apparatus is not to be confused with those devices which are designed to take air from the outside of a building and condition it before it is circulated within the building. Such devices are from their nature large, require special rooms for their

installation, require constant attention, and are expensive, not only as regards their first cost but as regards their operation.

70 My device is, as hereinbefore pointed out, of a semi-portable nature, and may be located in the room in which the air is to be treated. Any number of my devices may be used in a single room, and so placed therein as to give the maximum desired effect.

75 The first cost of my apparatus is relatively low, and the operating cost thereof practically negligible.

80 It is within the province of my invention to circulate a cooling medium instead of a heating medium through the heat-exchanger, thus adapting the apparatus to cooling and humidifying the air, as would be desirable during the summer months, or in installations where room temperature is normally high. This change from heating to cooling 85 can be made with no changes in the apparatus other than adjustment of the thermostat to close the circuit through the motor 2 and valve 23 when room temperature becomes too high.

90 It is to be noted that another advantage of the use of the heater with my humidifier resides in the fact that additional evaporation from the humidifier is thereby made possible for, as is well known, it takes more 95 water to produce the same relative humidity at higher temperatures than at low temperatures.

95 100 It will thus be seen that I provide a very simple and relatively inexpensive air conditioning apparatus, capable of performing all of the functions of the more costly and cumbersome plants now in use, and having marked advantages thereover, in that whereas such plants supply air at the same temperature and humidity for all rooms in a building fed thereby, my devices are placed in the rooms themselves and are subject to and controlled by conditions in such rooms or the parts of such rooms in which they and 105 their control devices (the thermostat and humidostat) are located.

110 Various changes are contemplated as within the spirit of the invention and the scope of the following claims.

115 I claim:—

120 1 In an air conditioning apparatus, a heat-exchanger, a humidifier, a motor and a fan driven thereby and operatively associated with said heat-exchanger and said humidifier and adapted to cause circulation of air through said heat-exchanger and said humidifier, and means for automatically controlling the operation of said heat-exchanger and said humidifier and therewith of said motor independently of each other or simultaneously in response to temperature and humidity conditions of the air to be treated.

125 2 In an air conditioning apparatus, a humidifier of the type including a rotatable 130

disk to which water may be delivered and atomizing projections arranged at the periphery of said disk, a motor having said disk mounted at one end of the armature shaft thereof, a fan secured to the other end of said motor shaft for directing a current of air towards said humidifier, a heat-exchanger so positioned adjacent said fan that the current of air established by said fan passes said heat-exchanger, a humidostat for controlling the supply of water to said disk, a thermostat for controlling the supply of a heating agent to said heat-exchanger, and a single supporting means for said humidifier, motor, fan and heat-exchanger, whereby said apparatus constitutes a unitary semi-portable structure capable of installation in any desired location.

In testimony whereof, I affix my signature.

FREDERIC F. BAHNSON.
